UNITED STATES PATENT OFFICE

JUNIUS H. STONE, OF PORT WASHINGTON, NEW YORK

BUILDING CONSTRUCTION

Application filed March 28, 1929. Serial No. 350,507.

This invention relates to building construction.

My invention is particularly directed to the combined use with structural steel elements 5 of blocks of suitable wall material, such as so-called corkboard or other blocks of cork, and/or of molded compressed wood pulp, blocks of gypsum, cement blocks, and the like. Such materials usually and preferably possess 10 heat insulating qualities.

A salient feature of my invention is the use of steel members, preferably of present day standard shapes, and particularly of steel I-beams, serving as the vertical members, the 15 lower ends of the I-beam members being anchored in or bolted to concrete or similar foundation, the I-beams being spaced at determined distances from one another, the wall blocks mechanically spanning between the 20 I-beams and interlocked therewith by providing slots at the opposite vertically disposed edges of the blocks embracing the opposite flange portions of the steel members, the resulting joints being suitably 25 bonded and sealed.

Corkboard of present day standard dimensions is most conveniently employed by locating the vertical steel members at corresponding horizontal spacings, the vertically disposed edges of the individual corkboards being slotted in correspondence to the flanges of the vertical I-beams, each individual cork 30 board being assembled to position by passing it at the tops of the two I-beams of its span 35 over the opposing flanges, and allowing the blocks to drop seriatim to their assembled positions.

Grout or other cementitious material is 40 then poured between the slot faces and the flange faces to permanently position the boards and seal the joints. At desired intervals, suitable straps of steel or like mechanical means may be employed to reinforce the mechanical interlocking between the vertical 45 steel members and the thus formed wall portions.

My invention is advantageous in locating the corkboard or other blocks of wall material at the exterior of the building wall, 50 which serve as the support for any desired

finish, as by the use of expanded metal secured by nails, wires or the like to the blocks, and stucco applied to the expanded metal.

The interior wall may be formed as desired. My construction lends itself admirably to 55 the use of suitable supporting material, such as so-called ribbed metal lath which is mechanically secured to the inwardly disposed flanges of the I-beams or other vertical shapes, and plaster or other desired finish wall ma- 60 terial secured to such support.

My invention is also applicable for employing the corkboard or other wall block material as the inner wall, the plaster being 65 secured thereto by expanded metal or the like interposed between the corkboard and the plaster. In the latter form of my invention, the outer wall material may be formed of stucco secured in position to a suitable supporting material such as expanded metal, in 70 turn mechanically secured to the outer flange of the vertical steel shapes.

In the form of my invention in which the wall blocks form a part of the inner wall, the exterior finish may be of the clapboard 75 type, or of the shingle type, by employing vertical wooden strips secured to the outer flanges of the steel I-beams, the boards or other sheathing being nailed to the vertical strips, and the outer finish secured to the 80 sheathing, as is understood by those skilled in the art.

A particular feature of my invention is the provision of dead air spaces between the outer and inner walls of the respective spans 85 between the vertical steel members.

Further features and objects of the invention will be more fully understood from the following detail description and the accompanying drawings, in which

Fig. 1 is a detail side elevation of a portion of a wall and corner of a building construction embodying my invention, the respective constituent materials being exposed to view;

Fig. 2 is a sectional elevation on line 2—2 of Fig. 1;

Fig. 3 is a sectional elevation on line 3—3 of Fig. 1;

Fig. 4 is a sectional elevation similar to that of Fig. 3, but showing a corner assembly with

a side wall and a ceiling and an intermediate floor;

Fig. 5 is a detail vertical sectional elevation of a corner assembly with the vertical wall of the uppermost ceiling and roof;

Fig. 6 is a detail horizontal view illustrating one method of supplemental mechanical reinforcement; and

Fig. 7 is a detail sectional elevation similar to Fig. 2, but showing a modification.

Referring to the embodiment of my invention illustrated in Figs. 1 to 5 inclusive, the foundation 10 is usually of concrete but may be of any desired foundation material. The vertical steel members 11, preferably I-shapes, are anchored at their bottom ends within the foundation material 10 or suitably bolted thereto in position.

In this form of my invention the blocks 20 of wall material, such as corkboard, blocks of gypsum, compressed wood pulp, lumber, tile, concrete or the like form the outer walls or wall sections. Such individual blocks 14, see Fig. 1, are of a dimension to span from 25 and between the vertical steel members 11, the vertical lateral faces of the individual blocks 14, see Fig. 2, being slotted as is indicated at 15, to receive and embrace the outer flange 16 of the respective pairs of vertical steel members 11. The slots 15 are preferably 30 over-dimensioned to freely receive the flange portions 16, the individual wall blocks 14 being assembled in interlocking relation with the steel members by passing said blocks individually at the upper termini of the flange 35 edges of the vertical steel members 11, and allowed to drop down to the required position seriatim, thus gradually building up the respective wall portions by interlocking between and with the vertical steel members.

Upon assembling the individual wall blocks 14 to position, grout or other cementitious or hardening plastic material is applied within the joints between the faces of the slots 45 15 and the faces of the flange portions 16, thus permanently securing the wall blocks in position and sealing the joints, as indicated at 30, see Fig. 6.

The desired finish material is applied to the outer face of the corkboard or other wall block material. For a stucco finish, expanded metal lathing 17 may be nailed or otherwise secured to the wall blocks and stucco 18 is applied to the metal lathing.

For the inner wall finish, usually plaster 19, a suitable support for the same is mechanically secured to span from and between the inner flanges 20, 20, adjacent I-beams 11, as by the use of ribbed wire mesh 22 or the like which is bolted or otherwise suitably attached. The plaster 19 is suitably applied to the wire mesh or such other support 21.

If desired, the mechanical interlocking between the wall blocks and the I-beams may be reenforced by mechanical straps, see Fig.

6, as by oppositely disposed wires 22 extending from the inner faces of the outer flanges 16 of the I-beams 11, thence about the outer flange faces and between abutting lateral faces of adjacent wall blocks, the free ends 70 23 being twisted with one another or passed through meshes of the metal lathing 17 or equivalent support for the outer finish material.

My construction lends itself admirably for 75 securing suitable metal shapes and/or wood beams for supporting the respective floors, ceilings and the roof. Fig. 3 illustrates a typical assembly for the first floor, the concrete or other foundation being indicated at 10, the floor beams 24 in this instance being illustrated as wooden beams each lodged at its ends upon the foundation 10 and secured to a horizontal L member 24 which may be bolted to the inner flanges of the respective 80 vertical I-beams 11.

A typical ceiling and intermediate floor assembly is illustrated in Fig. 4, the floor beams being indicated at 26 which may be wooden beams, each supported at its ends 90 upon horizontal L members 27, bolted to the I-beams 11. The ceiling may be of plaster 28 secured by expanded metal lathing 29 or the like.

A typical roof assembly is indicated in 95 Fig. 5, the upper horizontal edges of the I-beams 11 being indicated at 11a, adjacent which the horizontal steel beams 31 or other desired shapes are bolted in position to horizontal members 32 interspanning the vertical 100 I-beams 11. The roof is formed and supported upon the horizontal beams 31 pursuant to present practice or other desired assembly, as by bolting thereto the struts 33, to which are bolted or otherwise secured the 105 nailer strips 34, to which are then nailed the roof members 35, the finish roofing material being as desired.

By the assembly of the inner and outer wall materials, above described, there is provided in each span between adjacent vertical 110 steel members 11 the dead air spaces 36, see Figs. 2, 3, 4 and 5.

These air spaces facilitate the passing and installation of electrical wiring, plumbing, 115 piping and the like.

My invention is also applicable for employing corkboard or other blocks of wall material as the inner wall, as is illustrated in Fig. 7, the I-beams 11 being secured in 120 position upon the foundation similarly as above stated. The wall blocks 14 are similarly provided with slots 15, as above described, for receiving and embracing in this embodiment, the inner flanges 20 of the I-beams 11 in lieu of the outer flanges 16. The joints between the wall blocks and the I-beams are sealed similarly as above set forth. The finish material for the inner 125 wall, such as plaster 37, is applied to the ex- 130

panded metal lathing 38, by nailing or otherwise securing the same to the other face of the wall blocks. An outer finish such as stucco is applied and supported similarly 5 as above set forth.

Fig. 7 also illustrates the application of clapboard, shingles and the like, as the outer wall finish, which may be effected by bolting vertical strips 39 to the outer faces of the 10 outer flanges 16 of the I-beams 11, nailing a suitable sheathing 40 to such vertical strips 16 and applying the clapboard 41, shingles or the like.

Dead air spaces 36 are similarly provided 15 in this embodiment of my invention.

Whereas, I have described my invention by reference to specific forms thereof, it will be understood that many changes and modifications may be made without departing from 20 the spirit of the invention.

I claim:—

1. In a building construction, the combination of vertically extending structural elements of rigid material, said structural elements individually having outwardly and inwardly disposed vertically extending flanges, blocks of wall material having vertically extending slots at their vertically disposed sides receiving and embracing portions of 30 said outwardly disposed flanges, said blocks serving as the outer wall material, layers of plaster serving as the inner wall material and means for mechanically supporting the plaster from said inwardly disposed flanges 35 of said structural elements.

2. In a building construction, the combination of vertically extending structural elements of rigid material, said structural elements individually having outwardly and inwardly disposed vertically extending flanges, blocks of wall material having vertically extending slots at their vertically disposed sides receiving and embracing portions of 40 said outwardly disposed flanges, said blocks serving as the outer wall material, said blocks of wall material individually spanning from and between adjacent structural elements, layers of plaster serving as the inner wall material and means for mechanically supporting the plaster from said inwardly disposed flanges of said structural elements.

3. In a building construction, the combination of a foundation, steel structural elements having their lower ends secured to 45 said foundation, said structural elements having individually outwardly and inwardly disposed vertically extending flanges spaced from one another, blocks of wall material having vertically extending slots at their vertically disposed sides, receiving and embracing 50 portions of said vertically extending flanges, plaster serving as the finish of the inner wall material, and means for supporting said plaster from said inwardly disposed vertically extending flanges of said structural

elements, said construction providing for an air space between the outer and inner wall materials.

4. In a building construction, the combination of a foundation, steel structural elements having their lower ends secured to said foundation, said structural elements having individually outwardly and inwardly disposed vertically extending flanges spaced from one another, blocks of wall material having vertically extending slots at their vertically disposed sides, said blocks of wall material individually spanning from and between adjacent structural elements, receiving and embracing portions of said vertically extending flanges, plaster serving as the finish of the inner wall material, and means for supporting said plaster from said inwardly disposed vertically extending flanges of said structural elements, said construction providing for an air space between the outer and inner wall materials. 70

5. In a building construction, the combination of a foundation, steel structural elements having their lower ends secured to said foundation, said structural elements having individually outwardly and inwardly disposed vertically extending flanges spaced from one another, blocks of wall material having vertically extending slots at their vertically disposed sides, said blocks of wall material serving as outer wall material, receiving and embracing portions of said vertically extending flanges, plaster serving as the finish of the inner wall material, and means for supporting said plaster from said inwardly disposed vertically extending flanges of said structural elements, said construction providing for an air space between the outer and inner wall materials. 95

6. In a building construction, the combination of a foundation, steel structural elements having their lower ends secured to said foundation, said structural elements having individually outwardly and inwardly disposed vertically extending flanges spaced from one another, blocks of wall material having vertically extending slots at their vertically disposed sides, said blocks of wall material serving as the outer wall material, said blocks of wall material spanning from and between adjacent structural elements, receiving and embracing portions of said vertically extending flanges, plaster serving as the finish of the inner wall material, and means for supporting said plaster from said inwardly disposed vertically extending flanges of said structural elements, said construction providing for an air space between the outer and inner wall materials. 105

7. In a building construction, the combination of a foundation, steel I-beams having their lower ends secured to said foundation, said I-beams having individually outwardly and inwardly disposed vertically extending 110

130

flanges spaced from one another, blocks of wall material having vertically extending slots at their vertically disposed sides, receiving and embracing portions of said vertically extending flanges, plaster serving as the finish of the inner wall material, and means for supporting said plaster from said inwardly disposed vertically extending flanges of said I-beams, said construction providing for an air space between the outer and inner wall materials.

8. In a building construction, the combination of a foundation, steel I-beams having their lower ends secured to said foundation, said I-beams having individually outwardly and inwardly disposed vertically extending flanges spaced from one another, blocks of wall material having vertically extending slots at their vertically disposed sides, said blocks of wall material individually spanning from and between adjacent said I-beams, receiving and embracing portions of said vertically extending flanges, plaster serving as the finish of the inner wall material, and means for supporting said plaster from said inwardly disposed vertically extending flanges of said I-beams, said construction providing for an air space between the outer and inner wall materials.

9. In a building construction, the combination of a foundation, steel I-beams having their lower ends secured to said foundation, said I-beams having individually outwardly and inwardly disposed vertically extending flanges spaced from one another, blocks of wall material having vertically extending slots at their vertically disposed sides, said blocks of wall material serving as outer wall material, receiving and embracing portions of said vertically extending flanges, plaster serving as the finish of the inner wall material, and means for supporting said plaster from said inwardly disposed vertically extending flanges of said I-beams, said construction providing for an air space between the outer and inner wall materials.

10. In a building construction, the combination of a foundation, steel I-beams having their lower ends secured to said foundation, said I-beams having individually outwardly and inwardly disposed vertically extending flanges spaced from one another, blocks of wall material having vertically extending slots at their vertically disposed sides, said blocks of wall material serving as the outer wall material, said blocks of wall material spanning from and between adjacent said I-beams, receiving and embracing portions of said vertically extending flanges, plaster serving as the finish of the inner wall material, and means for supporting said plaster from said inwardly disposed vertically extending flanges of said I-beams, said construction providing for an

air space between the outer and inner wall materials.

11. In a building construction, the combination of vertically extending structural elements of rigid material, said structural elements individually having vertically extending flanges, blocks of wall material having vertically extending slots at their vertically disposed sides adapted to receive and embrace portions of said flanges, said blocks serving as wall material, layers of covering material serving as covering for the wall material and means for mechanically supporting the covering material from said structural elements.

12. In a building construction, the combination of vertically extending structural elements of rigid material, said structural elements individually having outwardly and inwardly disposed vertically extending flanges, blocks of wall material having vertically extending slots at their vertically disposed sides adapted to receive and embrace portions of said flanges, said blocks serving as wall material, layers of covering for the wall material and means for mechanically supporting the covering material from the flanges of said structural elements.

13. In a building construction, the combination of vertically extending structural elements of rigid material, said structural elements individually having vertically extending slots at their vertically disposed sides adapted to receive and embrace portions of said flanges, said blocks serving as wall material, layers of covering material serving as covering for the wall material and means for mechanically supporting the covering material from the flanges of said structural elements.

In testimony whereof I have signed this specification this 19th day of March, 1929.
